UNITED STATES PATENT OFFICE.

LEON T. J. LUBIN, OF BOSTON, MASSACHUSETTS.

INSTEP-SUPPORT OR ARCH-PROP.

No. 892,066.

Specification of Letters Patent.

Patented June 30, 1908.

Application filed April 2, 1906. Serial No. 309,327.

To all whom it may concern:

Be it known that I, LEON T. J. LUBIN, a citizen of the United States, residing at Boston, county of Suffolk, and State of Massachusetts, have invented an Improvement in Instep-Supports or Arch-Props, of which the following description, in connection with the accompanying drawing, is a specification, like letters on the drawings representing like parts.

This invention has for its object the production of a novel instep support or arch prop, wherein the inner end of the arch prop or the end farthest from the heel is provided with a foot which adds materially to the stiffness at that end of the arch prop with relation to its width, and whereby that end of the arch prop may be raised more or less as is frequently necessary to adapt the arch prop to the requirements of the foot. The rear or heel end of the arch prop is provided with a spring portion integral with the metal forming the arch prop, said spring serving to throw the arch prop pressure away from the foot when the weight is removed.

Figure 1 shows an inner side elevation of an arch prop embodying my invention; Fig. 2 is a bottom side view of Fig. 1; Fig. 3 is a section on the line *x*, Fig. 2, and Fig. 4 is a cross section on the line *x'*, Fig. 1, looking toward the left.

The instep or arch prop herein represented comprises a sheet metal body part *a* and a non-metallic top or cover part of leather or other usual material *b*, said parts being attached one to the other by rivets *c*. The body part of the arch prop, which gives shape to the same, is curved in the direction of its length and width to fit the hollow of the foot or the under surface of the normal arch of the instep, a portion of said body part at its inner edge being curved upwardly to present a caved part next the instep of the foot. The front or inner end of the arch prop is shown as provided with a foot *a'* that crosses said arch prop. The foot may be separated more or less from the under side of the body part overlying the same to leave, as shown, a free space between the inner end of the body part

and the overlying top part or cover. The foot is shown as formed by bending the front end of the arch prop downwardly and backwardly on itself. Bending the arch prop backwardly in forming the foot leaves the arch prop of such construction and shape at its front end that it cannot cut the leather forming the sole of the shoe.

In practice the bend 2 may be more or less sharp to locate the foot at the distance desired with relation to the body of the arch prop thereabove according to the shape of the foot and the requirements for its proper support.

The metal of the arch prop may be more or less stiff, and in some instances it may be such as to permit the foot to yield somewhat. The crosswise foot adds to the stiffness crosswise of the arch prop at its front end, and this foot may be bent to change the height of the central part of the prop with relation to the sole of the shoe.

The rear end of the arch prop is slotted at 3, the slit being shown as circular, and the metal 4 within the circular slit is elevated as shown in Figs. 1 and 3 to form a spring member on which rests the under side of the leather top piece *b* with which the heel of the person wearing the shoe having the arch prop contacts. The metal 4 constituting the spring sustains the weight of the foot when walking, and when the foot is lifted from the ground, the spring resumes its normal position Fig. 1, and serves to remove the pressure of the top part *b* of the prop from the arch of the foot.

Having fully described my invention, what I claim as new and desire to secure by Letters Patent is:

1. As an article of manufacture an instep support or arch prop comprising a metallic body portion shaped longitudinally and transversely to fit the arch of the foot, said arch prop being bent downwardly and backwardly across one end to form a foot the free end of which is normally out of contact with the under side of the arch prop and in front of the median transverse line thereof.
2. A metallic arch prop bent downwardly

and backwardly across one end to form a foot with a space between its end and the under side of the arch prop, said foot crossing the arch prop in front of the median line 5 of the normal arch of the instep, the opposite end of said arch prop being slotted to form a spring.

In testimony whereof, I have signed my name to this specification, in the presence of two subscribing witnesses.

LEON T. J. LUBIN.
